Primary Examiner — Rosemary K Tarcza(74) *Attorney, Agent, or Firm* — Banner & Witcoff, Ltd.(57) **CLAIM**

The ornamental design for a charger, as shown and described.

DESCRIPTION

FIG. 1 is a perspective front view of a charger, showing illuminable elements in a lightable sequence;

FIG. 2 is another perspective front view of a charger, showing illuminable elements in a lightable sequence;

FIG. 3 is another perspective front view of a charger, showing illuminable elements in a lightable sequence;

FIG. 4 is another perspective front view of a charger, showing illuminable elements in a lightable sequence;

FIG. 5 is another perspective front view of a charger, showing illuminable elements in a lightable sequence; and,

FIG. 6 is an alternative perspective front view of the charger from FIG. 5.

The broken line showing of the charger in is for illustrative purposes only and forms no part of the claimed design. The charger includes circular illuminable elements on the front face. Applicant recognizes inventive aspects of the charger, and portions thereof, with the circular elements illuminated in any of the single state illuminable patterns shown, or in the multi-state or sequence of illumination shown.

1 Claim, 3 Drawing Sheets---
